UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

HEEL-ATTACHING MACHINE.

1,051,797.

Specification of Letters Patent. Patented Jan. 28, 1913.

Application filed August 15, 1903, Serial No. 169,643. Renewed August 12, 1911. Serial No. 643,781.

To all whom it may concern:

Be it known that I, ARTHUR BATES, a subject of the King of England, and residing at Leicester, in England, have invented certain new and useful Improvements in or Relating to Heel-Attaching Machines, of which the following is a specification.

This invention relates to machines for operating on heels and is herein shown as embodied in a machine for attaching heels to boots or shoes.

With heel-attaching machines of a kind heretofore commonly employed in which the several lifts of a heel are attached to the shoe by parallel nails which are driven through the outer lifts into the inner ones in a direction perpendicular to them, certain classes of heels, for instance the tapered, coned or undercut heels of ladies' boots or shoes cannot be attached securely, for as in such heels the top and outer lifts are of an area considerably smaller than that of the heel-seat lift or offset forwardly with respect to the heel seat lift and as the attaching-nails have necessarily to be at a small distance within the outside edge of the top-lift, they will be at a greater distance within the edge of the heel in the heel-seat and therefore the heel-seat lift and the lift or lifts immediately above it having no nails passing through their outer or rear portions will not be securely held.

It is an object of the present invention to provide a machine by employing which this defect may be obviated and the attaching nails may be inserted in those portions of the heel which cannot be conveniently or effectively secured by nails driven from without the boot or shoe in a direction perpendicular to the outer lift. As shown herein, this result is effected by driving the attaching nails, or part of the attaching nails, into the heel inclined longitudinally of the heel with respect to the surface they first enter.

A further object of the invention is to provide means for engaging and securely holding during the operation of the machine a series of lifts constituting a heel when, as is the case in the heels of ladies' boots or shoes above referred to, the face of the outer

lift is at an angle with the face of the heel-seat lift.

The invention also contemplates a machine so constructed and arranged as to drive with precision attaching-nails through the heel-seat lift toward the outer lift, so that by the use of such a machine nails can be driven from within a boot into the rear part of a heel which is tapered, coned or undercut. By thus driving the attaching-nails or a portion of them into the rear part of a heel from within the boot, the rear portions of the heel-seat lift and of the lifts immediately adjacent are penetrated by them near the edges and the heel is much more firmly secured than when such portions of those lifts remain unperforated by nails which, driven from without as heretofore, perpendicularly through the lifts of a coned, tapered or undercut heel and parallel to one another, cannot be caused to extend through the marginal portions of the heel-seat and contiguous lifts.

According to the illustrated embodiment of the invention, there is employed in a heel-attaching machine for the purpose above described, the combination with a post or other convenient base and a work-support adjustable upon it, of a nail-driver arranged to drive a nail in a direction away from the work-engaging face of said support into the work supported thereby, and means to retain the support in position in which its work-engaging face shall be in oblique relation to the path of the driver, that is to say, in such relation that the path of the driver shall not be normal or perpendicular to the plane or surface of that face but shall have the same obliquity thereto as the nail is to have in relation to the face of the lift into which it is to be driven. By this construction the said support will be enabled to press against the contiguous face of a sole, for instance the inner face of an innersole, in such manner as to hold the further face of that sole closely against the whole oblique surface of a heel-seat lift adjacent and opposed to it and to grip this and the other lifts firmly by forcing them against a die-block or other abutment as will be hereinafter described, notwithstanding

ing the obliquity of the said surface in relation to the abutment. Further, after the heel is thus gripped, the nail-driver driving a nail in the line of its own motion and in a direction away from the work-engaging face will drive it through the sole and through the rear portions of the gripped heel-lifts. The arrangement by which the support is adjustable permits the obliquity 10 of the face of the support and the inclination of the attaching nails to be varied to suit the different requirements of the work.

In United States Letters Patent No. 1,000,957, granted August 15, 1911 upon 15 divisional application Serial No. 571,360, filed July 11, 1910, there is disclosed and claimed a machine constructed and arranged for driving all the attaching nails into a heel blank obliquely from within a boot. 20 As illustrated herein, however, one embodiment of the invention comprises a machine having drivers arranged to drive a portion of the attaching nails from within the boot into the outer portions of an oblique 25 heel-seat lift and other drivers arranged to drive attaching nails into the heel from without the top lift toward the heel-seat lift, preferably parallel with those driven in the opposite direction and within the outer 30 boundary of the top lift.

To this end an important feature of the invention consists in the provision of mechanism for driving heel attaching nails from within and from without a boot or shoe, in 35 combination with heel holding devices including a member having a work engaging face disposed obliquely to the path of the drivers.

As herein shown the member having the 40 obliquely disposed work engaging face comprises a plate apertured to permit the passage of the auxiliary drivers, or those which drive the attaching nails into the heel seat lift from within the boot, and said plate is 45 mounted in such a way that the inclination of its work-engaging face relatively to the path of the drivers may be varied as desired. Driver guiding tubes or nozzles, disposed in alignment with the drivers, are fixed in a 50 support with their ends projecting into the apertures of the oblique work-engaging plate, the apertures being so shaped as to permit angular movement of the plate relatively to the guiding tubes.

55 It is believed that heretofore a gang of tools has never been employed in a machine for operating upon heels as an element of the combination which includes a support with tool guiding devices fixed therein and 60 a work-engaging plate having apertures into which project said guiding devices, the plate being so mounted as to permit angular movement relatively to said fixed guiding devices, or so that the guiding devices are 65 inclined in the same general direction from

normals to the work-engaging face of the plate at the points at which the axes of the guiding devices intersect said face. Accordingly, this novel construction constitutes an important feature of the invention. 70 It will be apparent, moreover, that this feature of the invention is not limited in its use to a machine having mechanism for driving heel attaching nails from within and from without a boot or shoe, but is 75 capable of general application to any machine having tools for operating on a heel.

The work-support is preferably, according to the illustrated embodiment of this invention, mounted upon a post. The nail-driver for each nail to be driven obliquely toward and through the heel-seat lift may be a rod reciprocating in a guide, for instance, in a tubular nozzle which is held in or upon any firm support; conveniently the 80 post may be utilized to support the guide and also mechanism such as a driver-actuating head supported on and operated by a movable member of the heel-attaching machine for reciprocating the driver or drivers. 85 A vertical nozzle or tube may conveniently serve as a guide for a nail-driver reciprocated therein, the upper end of the nozzle when the upper end of the driver is retracted into it forming a socket in which 90 the nail is placed manually or mechanically, so as to rest upon the head of the driver, point uppermost. The work-support may be provided with holes or passages through 95 which the nails are driven from the nozzles. 100

In the description following, the subject-matter of the present invention is by way of example described in its application to a well-known type of heel-attaching machine in which a principal nail-driver and guiding and actuating devices therefor coöperate 105 to drive the majority of the heel-attaching nails from the outer face of the outer lift through the companion lifts in a manner which has heretofore been customary, the remainder of the attaching-nails being driven parallel to them obliquely through the heel-seat lift by apparatus constructed and operating according to the present invention, the nail-driving means in said apparatus thus becoming auxiliary in relation 110 to the principal nail-driver. 115

In the accompanying drawings:—Figure 1 is a front elevation of a heel-attaching machine of a well-known type with apparatus 120 according to the present invention applied thereto; Fig. 2 is a side elevation of the machine shown in front elevation in Fig. 1; Fig. 3 is a side elevation, partly in section (on the line 3—3 of Fig. 4), of a post which 125 has according to this invention an adjustable heel-support and nail-driving mechanism mounted upon it; this post is shown in position in the machine in full lines in Fig. 2 and in dotted lines in Fig. 1; above 130

the post in Fig. 3 are shown some heel-lifts *l* of an undercut heel and a die-block *G* or abutment against which the lifts are compressed by the post in the fashion herein-after explained; Fig. 4 is a rear elevation corresponding to the side elevation, Fig. 3, and partly in section; Fig. 5 is a plan of the adjustable work-support forming the upper portion of Figs. 3 and 4; Fig. 6 is a front elevation of a jack-carriage *I* forming a part of the machine illustrated in Fig. 1, movable in the frame of that machine and adapted to support the post illustrated in Figs. 1, 2, 3 and 4; Fig. 7 is a sectional plan 15 on the line 7—7, Fig. 6; Figs. 8 and 9 are views at right angles to one another of a slider employed for a purpose hereinafter described in the jack-carriage illustrated in Figs. 6 and 7; Figs. 10 and 11 are views at 20 right angles to one another of a shaft *h* mounted in the machine and hereinafter again specifically referred to; Fig. 12 is a view in perspective of a heel in which attaching nails have been inserted. Figs. 1 25 and 2 are on a smaller scale than that to which the whole of the remaining figures are drawn.

Like letters and reference-numerals indicate like parts throughout the drawings.

30 With reference to Figs. 1 to 11, a description will first be given of such portions of those figures as are well known, are described in the specification of prior Letters Patent of the United States to Joseph 35 Horace Pope No. 446885, and are not in themselves of the present invention, that is to say:—The main frame *A* of the heel-attaching machine has a driving shaft *B* journaled in suitable bearings. This driving 40 shaft is rotated by any usual or convenient means. Upon the driving shaft is an eccentric *B*⁸ surrounded by an eccentric strap *B*⁹, the lower end of which is pivoted at *e* to a lower head or cross-piece *E*, guided in bearings in the lower front portion of the frame 45 *A*. To said lower head *E* are secured upwardly-extending rods *E*¹, to the upper ends of which is secured a head or cross-piece *F*. Principal nail-drivers *F*¹ are secured upon 50 the head *F*. A stationary perforated die-block *G* is secured to the frame or standard *A*. This die-block, described in the specification of Patent No. 446885 aforesaid, is utilized for the purpose of the present invention 55 as the abutment or one of the work engaging members herein referred to. It has perforations in it corresponding in number and position with various dispositions of the drivers *F*¹ made according to the number and location of the nails to be driven in the heel. Loaders *M*¹ deliver heel-attaching nails into the perforations in the die-block *G*, the loaders being provided with means whereby their nail perforations may 60 also be suited to the number and disposi-

tion of the drivers employed at any time. A stationary block or projection *A*⁴ forms a part of the front portion of the frame *A*. At a point above such stationary block is arranged a vertically-movable block *H*, adapted to slide up and down in guides on the front portion of the machine and referred to hereinafter as the jack carriage support. On the top of the block *H* is supported the lower end of a vertical jack-screw *i* the 70 upper end of which works in a female screw-thread in a jack-carriage *I* having ways *w* on its upper side on which a post *K* is adapted to slide out and in. The jack screw *i* is preferably formed with a pinion on its 75 lower end and may be rotated from a treadle suitably connected with a rack meshing with the pinion, as in the construction disclosed in said patent above mentioned.

80 Clamps *c* are secured to the under side of the die-block *G* to receive all the lifts (for example the lifts *l*, Figs. 1 and 3) constituting a heel, with the exception of the top-lift which is spanked into place upon them after the other lifts have been nailed to the 85 shoe and is held in a top-lift holder with which the present invention has no concern and which therefore is not herein described.

90 Mounted upon the upper end of the post *K* is a movable work-support *K*¹ pivoted to it by the transverse pivot pin *k* and adapted to support upon its work-engaging face *k*⁹ the heel end of the sole or innersole *b* of a boot placed over the head of the post in the manner indicated in Fig. 3; *k*³ 100 is an adjusting screw in a screw-threaded hole in the upper end of the post *K* and bearing against the underside of the work-support *K*¹, which support it can adjust about the pivot-pin *k* to the desired angle, 105 the screw moving the work-support upward about the pivot-pin *k* or allowing it to move downward about the pin under the influence of gravity. The boot having been thus positioned on the post, the adjusting-screw *k*³ 110 having been turned to cause the face *k*⁹ of the support *K*¹ to assume a position in which it will bear fairly against the slanting heel-seat, and the post *K* having been moved in the ways *w* of the jack-carriage *I* to bring 115 its upper end with the heel-seat of the sole or innersole immediately above it underneath the perforations of the die-block *G*, the post is next forced upward to a height varying with the different heights of heel 120 so as to bring the heel portion of the boot or shoe sole against the under or slant side of the series of heel lifts held by the heel clamps *c*. This upward movement of the post is effected by a rotation of the jack-screw *i*, which moves the jack-carriage *I* upward away from the vertically-movable block *H* and from the shaft *h* journaled 125 therein, that is to say, in a direction which is transverse to the axis of the shaft *h*. One 130

of the filled loaders M^1 is next swung into position above the die-block G so that its perforations coincide with those of the said die-block. The loader is then discharged 5 allowing its nails to drop into corresponding perforations in the die-block with the nail-points resting on the heel. The head F is then moved downwardly for about one half of its stroke, and during such motion 10 the heel is automatically and firmly held between the under-face of the perforated die-block G and the sole of the boot b by a further upward movement of the post K , a movement due to a rise of the block H , 15 which moves the screw i endwise and thus applies a thrust therethrough to the jack-carriage I and post K which firmly compresses the lifts of the heel between the under-face of the die-block G and the post 20 and shoe-sole and holds the heel, shoe and post firmly in position during the nailing operation. The motion of the head or cross-piece F continuing, the principal nail-drivers F^1 drive the nails from the die-block into the heel and sole and cause the points of the nails to be clenched against the upper or work-supporting face of the work-support K^1 . If a top-lift is afterward 25 to be spanked on to the heel, the nail-heads are left slightly projecting above the heel as is common in this art. The shaft h in 30 the block H is oscillated in its bearings in time with the rise and fall of the block H , that is to say, it rotates in the direction of 35 the arrow thereon (Fig. 1) through an arc of say about 20° when the block H rises, and in the reverse direction to the same extent when the block descends; the shaft h is given this kind of oscillation by reason 40 of its employment as part of a mechanism for bringing about the rise and fall of the block H , such mechanism forming no part of the present invention.

The heel-attaching machine and the operations of its parts as thus far described in detail are not of the present invention; they effect the attaching of heels in a manner well understood and by nails which, like the nails X in Fig. 12, are perpendicular to 45 the several lifts, parallel to one another, and within the boundary of the smallest of those lifts. Still with reference to Figs. 1 to 11, but having regard now to improvements according to the present invention 50 whereby the remainder of the attaching-nails, for example the nails Y of Fig. 12, can be driven in the direction of the outer lift which is at an angle to the outer lift and to the 55 nails that varies in different kinds and sizes of work:—Below the level of the work-support K^1 are drivers 1, 2, which, inasmuch as the nail-drivers F^1 are regarded as the principal drivers, may in the present in-

stance be termed auxiliary nail-drivers, although, as will hereinafter be made clear, the drivers 1, 2 might be employed as the only nail-drivers in a machine unprovided with the principal nail-drivers F^1 . Only one of the plurality of auxiliary drivers 65 1, 2, which are similar in construction and operation, will herein be particularly described, for the construction and mode of operation of its companion will thereafter be understood without the need for further 70 75 description. Moreover it is within the present invention to employ only one such driver in a heel-attaching machine.

The auxiliary driver 1 normally occupies a position in which its upper end is retracted 80 within a tubular guide or nozzle 3, so that the space in the nozzle between the mouth thereof, which projects above the post, and said upper end of the driver constitutes a receptacle into which an attaching nail Y 85 is placed manually, or by mechanical means forming no part of the present invention, so as to rest as shown upon the head of the driver, point upward. The upper ends 3* of the nozzles 3 extend through the pivot-pin k which is fixed and into holes k^x in the support K^1 , which, as aforesaid, is movable. In order that the upper ends of these nozzles may not impede the movement of the support K^1 about the pivot-pin k the 90 holes k^x are elongated by slightly bell-mouthing them in planes transverse to the axis of the pin k , as shown in Figs. 3 and 5. The driver is forced rapidly upward 95 through the guide or nozzle 3 driving the nail in the line of motion of the driver and in a direction away from the work-supporting face k^y of the support K^1 obliquely into the lifts l , Fig. 3, which rest upon it and are compressed as aforesaid between the under-face of the die-block G and the shoe-sole. 100 It will be observed that the auxiliary driver 1 is arranged to drive a nail into a portion of the heel outside the lift of smallest area. The auxiliary driver 2 rises simultaneously 110 with the auxiliary driver 1 and drives the other of the two nails Y in the same manner. As will appear from the construction described, the nails driven by the auxiliary drivers are inserted simultaneously with the 115 insertion of the nails from without the shoe. The auxiliary drivers 1, 2 rest upon a driver-actuating device, which is the head or driver block 4 of a reciprocating plunger 5 contained within the post K and forming 120 part of a nail-driving mechanism whereby the drivers are reciprocated. To the lower end of this plunger is attached a plate 6 extending toward the front of the post and provided with a tubular extension 7 sliding 125 within a guide 8 forming part of the post and containing a spring 9 in compression between the lower portion of the extension

and a pin 11 passing through a slot 12 in the upper portion thereof and fixed in the post K. This spring 9 is for the purpose of insuring the return of the plunger 5 to the lower limit of its travel after each driving operation. The upward movement of the plunger 5 may be effected at intervals as desired by and convenient means commonly known in the mechanic arts, for instance, 5 by a moving member of the heel-attaching machine such as the shaft h which is operatively connected to and driven from the shaft B, hereinbefore referred to, by devices described in detail in the specification 10 of Patent No. 446885 aforesaid. By way of example one form of a mechanism whereby the said shaft h effects the operation of the plunger 5 is hereinafter described.

In the construction of post hereinbefore 20 described the work-support K¹ is provided with an adjusting-device to set the support obliquely, and with nail-driving means, as described; that these parts are mounted on the post is a practical convenience in that 25 their proper correlation is not affected by shifting a post out of one attaching machine into another, hence such a shift involves but a brief expenditure of time and does not necessitate the employment of skilled labor. 30 The face of the die-block or abutment G against which the heel-lifts are compressed need not be horizontal. It may be sloped or shaped in any convenient manner which will cause it to afford a fair bearing to the 35 outer lift of a heel presented to it at an angle by the work-support K¹. A handle 5^x projects through a slot K^x to the exterior of the post from the plunger 5; it is used to raise the plunger manually to lift the 40 drivers far enough to enable the operator to ascertain, if in doubt, whether they have all been supplied with nails or not.

One form of operative connection between 45 the plunger 5 of Figs. 3 and 4 and the shaft B of a heel-attaching machine such as is shown in Figs. 1 and 2 can be arranged as follows (see Figs. 1 to 11):—In the block H is the driver-actuating shaft h adapted to oscillate in the manner hereinbefore described. 50 Fixed on one end of that shaft is an arm 13 connected by a link 14 to one arm 15 of a bell-crank lever 15—16 pivoted at 17 on one (17) of a pair of studs 17, 18, by which a cover plate 19 is secured upon the 55 face of the jack-carriage I. Behind the cover plate 19 and guided partly by a groove 20 therein and partly by another groove 21 in the face of the jack-carriage is a slider 22, shown in detail in Figs. 8 and 9, in which 60 is a hardened roller 23 which has a running fit in a hole therein; the lower part of the slider is partly cut away to leave a shoulder 24 through which a portion of the periphery of the said roller projects; this roller rests

upon the arm 16 of the bell-crank lever 15 65 16, and the upper end 25 of the slider bears against the underside of the plate 6 which projects as aforesaid from the plunger 5 (Figs. 3 and 4). The shaft h is oscillated in the block H by mechanism which, as 70 aforesaid, forms no part of the present invention and is operatively connected with the main driving-shaft B of the machine. When it moves in the direction of the arrow shown near it in Fig. 1, it moves, by means 75 of the link 14, the bell-crank lever 15 16 so that the arm 16 thereof moves upward, lifting the slider 22, which, acting against the plate 6 on the plunger 5, lifts the latter and with it the head 4 and auxiliary nail-drivers 1, 2. Movement of the shaft h in a direction opposite to that which is indicated by the arrow near it in Fig. 1, causes the arm 16 of the bell-crank lever to move downward into the position in which it is 85 shown in that figure, so that it lowers the slider 22 and permits the spring 9, Fig. 3, to depress the plunger 5 and cause the head 4 thereof to lower the auxiliary nail-drivers until their upper ends are retracted into the 90 guides or nozzles 3.

The arm 15 of the bell-crank lever 15, 16, or any movable member which is the equivalent thereof, and like it is mounted upon the jack-carriage I and operatively connected 95 with the plunger, may be connected with another member such as the arm 13, in operative connection with the shaft h, by a link 14 pivoted to and connecting the parts 15 and 13, and if care be taken to dispose 100 this pivoted link at approximately a right angle to the path of motion of the jack-carriage, which path is vertical in the example illustrated, and approximately in the line in which the link 14 has to move in 105 transmitting the motion of part 13 to part 15, it will be found that either no angular motion at all, or an angular motion so small as to be negligible, is imparted to the bell-crank 15 16 by reason of its movement of 110 translation upward and downward with the jack-carriage I, but that nevertheless the movement of translation is not interfered with neither is the bell-crank 15 16 taken thereby out of a relationship to the arm 13 115 which is such as to permit of the instant angular movement of the bell-crank in response to angular movement of the shaft h, such movement taking place, moreover, through an angle which is constant or approximately so for a given angular movement of the shaft h, no matter to where the pivot 17 of the bell-crank lever may have been shifted within the limits of the small movement of translation imparted to it in 120 the rise and fall of the jack-carriage I. The feature of this arrangement which is novel in a heel-attaching machine is that the 125

length of stroke of the nail-drivers 1, 2 or 10 imparted to them by the slider 22 and plunger 5 moving in company remains practically constant in relation to the post K and 5 unaffected by the different amounts of vertical adjustment received by that post for different heights of heel.

What I claim as my invention and desire to secure by Letters Patent is:—

- 10 1. In a heel-attaching machine, the combination with a principal nail-driver and guiding and actuating devices for that nail-driver, of a base, a work-support adjustable upon it, auxiliary nail-driving means to drive a nail in a direction away from the work-supporting face of said support into the work supported thereby, and means for retaining the support in positions in which its work-supporting face shall be in oblique 15 relation to the path of the driver.
- 20 2. In a heel-attaching machine, the combination with an abutment, a principal nail-driver, and guiding and actuating devices for that nail-driver, of a base, a work-support adjustable upon it, auxiliary nail-driving means to drive a nail in a direction away from the work-supporting face of said support into the work supported thereby, and means for retaining the support in positions in which its work-supporting face shall be in oblique 25 relation to the path of the driver.
- 30 3. In a heel-attaching machine, the combination with a principal nail-driver, and guiding and actuating devices for that nail-driver, of a base, a work-support adjustable upon it, auxiliary nail-driving means to drive a nail in a direction away from the work-supporting face of said support into the work supported thereby, and means for retaining the support in positions in which its work-supporting face shall be in oblique 35 relation to the path of the driver.
- 40 4. In a heel-attaching machine, the combination with a principal nail-driver, guiding and actuating devices for that nail-driver and a post, of a work-support adjustably mounted upon the post, a nail-driving mechanism upon the post comprising an auxiliary driver to drive a nail in a direction away from the work-supporting face of said support into the work supported thereby, and means for retaining the support in positions in which its work-supporting face shall be in oblique 45 relation to the path of the auxiliary driver.
- 50 5. In a heel-attaching machine, the combination with an abutment, a principal nail-driver, guiding and actuating devices for that nail-driver and a post, of a work-support adjustably mounted upon the post, nail-driving mechanism upon the post comprising an auxiliary driver to drive a nail in a direction away from the work-supporting face of said support into the work supported thereby, and means for retaining the support in positions in which its work-supporting face shall be in oblique 55 relation to the path of the auxiliary driver.
- 60 6. In a heel-attaching machine, the combination with an abutment, a principal nail-driver, guiding and actuating devices for that nail-driver, and a post, of a work-support adjustably mounted upon the post, nail-

driving mechanism upon the post comprising an auxiliary driver to drive a nail in a direction away from the work-supporting face of said support into the work supported thereby, and means for retaining the support in positions in which its work-supporting face shall be in oblique relation to the path of the auxiliary driver.

6. In a heel-attaching machine, the combination with a principal nail-driver, guiding and actuating devices for that nail-driver, and a post, of a work-support adjustably mounted upon the post, nail-driving mechanism upon the post comprising an auxiliary driver to drive a nail in a direction away from the work-supporting face of said support into the work supported thereby, means for retaining the support in positions in which its work-supporting face shall be in oblique relation to the path of the auxiliary driver, an abutment and mechanism whereby the distance between the post and abutment is varied.

7. In a heel-attaching machine, the combination with a principal nail-driver, guiding and actuating devices therefor, and a post, of an adjustable work-support, a tubular nozzle, an auxiliary nail-driver in the nozzle, mechanism for reciprocating the auxiliary nail-driver, and means for retaining the support in positions in which its work-supporting face shall be in oblique relation to the path of the driver.

8. In a heel-attaching machine, the combination with a principal nail-driver, guiding and actuating devices therefor, of an adjustable work-support provided with a passage for a nail, an auxiliary nail-driver, means which operate it to drive a nail out of said passage in a direction away from the work-supporting face of said work-support into the work supported thereby, and means for retaining the support in positions in which its work-supporting face shall be in oblique relation to the path of the auxiliary driver.

9. In a heel-attaching machine, the combination with a post, and an adjustable work-support, of a nozzle fixed in the post, a nail-driver in the nozzle with its upper end retracted within said nozzle so that the space in the nozzle between the mouth thereof and said upper end of the driver constitutes a receptacle for a nail, mechanism for reciprocating the driver, and means for retaining the support in positions in which its work-supporting face shall be in oblique relation to the path of the driver.

10. A machine for attaching heels, having in combination, means for holding a heel under pressure upon the heel seat of a shoe, mechanism for automatically driving heel attaching nails from without the shoe through the heel and into the heel seat and mechanism for simultaneously driving heel

attaching nails automatically from within the shoe at the rear of the nails driven from without.

11. In a heel-attaching machine, the combination with mechanism for driving nails from without and within a boot or shoe into a heel in a direction perpendicular to its tread face, of means for holding the heel under pressure upon the boot or shoe in attaching position, said means being arranged for adjustment to permit heels with heel seat faces of different degrees of inclination with relation to their tread faces to be sustained in attaching position.

12. A heel attaching machine, having, in combination, means for supporting a shoe and a heel under pressure in heel-attaching position, mechanism for driving heel-attaching nails from without the shoe through the heel into the heel seat and mechanism for driving heel-attaching nails from within the shoe into a portion of the heel at the rear of the nails driven from without the shoe and in a direction inclined forwardly of the shoe.

13. A machine for attaching heels, having in combination, means for positively forcing a heel upon the heel seat of a shoe, mechanism for thereafter automatically driving heel attaching nails from without the shoe through the heel and into the heel seat and for clenching said nails upon the interior of the shoe, and mechanism for driving heel attaching nails automatically from within the shoe at the same time that nails are driven from without the shoe.

14. A machine for operating on heels, having, in combination, a pressure resisting member, a driver block and drivers mounted for reciprocation toward and away from said pressure resisting member, a support having apertures to permit the passage of the drivers, driver-guiding tubes fixed in said support and projecting therefrom toward said pressure resisting member, and a work engaging plate so connected with said support as to permit angular movement of the plate relatively to said projecting tubes and having apertures to receive said tubes.

15. A machine for operating on heels, having, in combination, a pressure resisting member, a tool block and tools mounted for reciprocation toward and away from said pressure resisting member, a support, an apertured work engaging plate having a transverse pivot at one side whereby it is connected to said support, an adjustable stop constructed and arranged to engage said work engaging plate adjacent to its other side for sustaining said plate with its work engaging face inclined with respect to the path of the tools, and tool-guiding devices fixed in said support and projecting into the apertures of said work engaging plate.

16. A machine for operating on heels, having, in combination, a pressure resisting member for engaging one side of a heel, a gang of tools located on the opposite side of the heel and mounted to reciprocate toward and away from said member, a plate having a work engaging face oblique to the path of said tools and provided with perforations in alinement with said tools, a member having rigidly set therein tool guiding devices which extend into the perforations of said plate, and adjustable means for determining the operative position of said plate.

17. A machine for operating on heels, having, in combination, a pressure resisting member for engaging one side of a heel, a plate located on the opposite side of the heel and having a substantially plane work-engaging face, said plate being mounted for movement toward said member to press the work against said member and arranged with its work engaging face oblique to its path of movement, a support for said plate, and a plurality of tool guiding tubes set rigidly in said support and inclined in the same general direction from normals to the work engaging face of the plate at the points at which the axes of the tubes intersect said face.

18. A machine for operating on heels, having, in combination, a pressure resisting member, a tool block and tools arranged to reciprocate toward and from said member, a supporting member, an apertured work engaging plate having a transverse pivotal connection at one side with said supporting member, and tool guiding devices fixed in said supporting member and projecting into the apertures of said work engaging plate.

19. A machine for operating on heels, having, in combination, a pressure resisting member, a tool block and tools arranged to reciprocate toward and from said member, a support having fixed therein tool guiding tubes projecting toward said pressure resisting member in alinement with said tools, and a work engaging plate pivotally connected with said support and provided with apertures for the reception of said guiding tubes so shaped as to permit angular movement of said plate relatively to said tubes.

20. A machine for operating on heels having, in combination, drivers, actuating mechanism for reciprocating the drivers, separate driver-guiding tubes each having a uniform internal diameter for the full length of the driver stroke and being arranged to receive the nails to be driven, a recessed plate into which the outer ends of the driver guiding tubes project, a supporting member in which the opposite ends of the tubes are rigidly set so as to occupy at all times a fixed relation, and a work engaging member oppo-

sitely disposed with respect to the recessed plate, said recessed plate being arranged to move toward the oppositely disposed work engaging member preliminarily to the operation of the drivers.

In testimony whereof I have signed my

name to this specification in the presence of two subscribing witnesses.

ARTHUR BATES.
